UNITED STATES PATENT OFFICE.

CARL HOLBORN, OF GÖTTINGEN, GERMANY.

PENHOLDER AND OTHER FINGER-HELD TOOL.

No. 824,863.

Specification of Letters Patent.

Patented July 3, 1906.

Application filed December 15, 1905. Serial No. 291,890.

To all whom it may concern:

Be it known that I, CARL HOLBORN, a subject of the German Emperor, residing at Göttingen, in the Empire of Germany, have invented certain new and useful Improvements 5 in Penholders and other Finger-Held Tools, of which the following is a specification.

This invention relates to penholders, pencil-holders, artists' brushes, engraving-tools, 10 knitting-needles, crochet-hooks, and other finger-held tools or instruments.

The purpose of the invention is to construct them in a novel manner, so as to provide the operative finger of the user with a support 15 which insures steadiness and accuracy in working and which is adapted to prevent the unintentional movements, contractions, and twitchings of the fingers to which nervous people and those suffering from writers' 20 cramp or the like are subject when using the tools or instruments in question.

The invention is also useful for instructing children in the manner in which penholders should be held during writing.

25 The invention is illustrated in the annexed drawings, in which—

Figure 1 represents a penholder, partly in section, constructed with the improved finger attachment. Fig. 2 represents the two annular parts forming the finger attachment.

As shown in the drawings, the penholder or similar instrument is made in separable parts and comprises the two rings *a*, forming 35 the finger attachment. These are of different diameters, corresponding to the shape of the finger to be inserted thereinto. The said rings can be made of vulcanite aluminium with india-rubber lining or other suitable material and are fixable to the penholder in such 40 a manner that when the user's forefinger has been inserted into the said rings the penholder is firmly connected with the said finger. There is therefore no necessity for the writer to exert the tight grip or hold which is 45 usually the cause of writers' cramp and of bad unsteady handwriting.

For the purpose of fixing the rings to the penholder the said rings are provided with 50 perforated lugs *c*, adapted to be engaged between a center piece *d*, which forms part of the said holder, and the end parts *b* of the latter screwed to the center piece. The center piece *d* is exchangeable the length thereof, being selected according to the length of the 55 user's finger. If desired, small perforated

disks or distance-pieces can be added to regulate the distance between the two rings. The arrangement described can be modified by fixing the two rings in juxtaposition at that end of the center piece *d* which is nearest to 60 the nib, the said two rings serving for the reception of the forefinger and thumb, respectively. These two rings can be of substantially equal size, owing to the similarity between the thickness of those parts of the 65 thumb and forefinger which are inserted into said rings. This arrangement allows of holding the pen with great steadiness without exerting any pressure whatever.

As has already been indicated, the improved finger attachment described can also be used in connection with pencils, brushes, engraving-tools, knitting - needles, crochet-hooks, and the like and in all cases reduces to a minimum the strain on the muscles of the 70 hand holding the tool or instrument in question, so that the said tool or instrument can be controlled with great steadiness and accuracy. The fact that the rings forming the finger attachment are angularly or rotarily 75 adjustable allows of using a penholder provided with said attachment for various styles of handwriting—for instance, for writing with a backward slant or in Gothic characters. For this purpose the rings are so adjusted that when the finger has been inserted thereinto in the normal manner the position of the penholder is suitable for the style of writing required. It is obvious that rings 80 for the forefinger and thumb can be used separately or together, so that the improved finger attachment can, for instance, be used by persons who have lost or injured either the forefinger or thumb of the hand required for holding the tool.

Annular finger attachments for penholders and pencils are not in themselves novel. The novelty of the present invention lies in the arrangement which allows of fixing rings of any desired size to a penholder or other tool 85 by means of a detachable center piece which forms part of the said tool, the rings being engaged between the said center and end pieces in such a manner that they are rotarily adjustable and that the distance between them 90 can be altered by altering the length of the center pieces or by using distance-pieces in combination with the latter.

I claim as my invention—
In a holder for finger-operated tools the 110

combination of a center piece and two end pieces, screws axially positioned in said pieces for attachment thereof to one another and two rings having each an eye adapted to encircle said screws and to be clamped thereby intermediate of said center and end pieces substantially as set forth.

In witness whereof I have signed this specification in the presence of two witnesses.

CARL HOLBORN.

Witnesses:

FLORENCE FULLER,
LOUISE SHRODER.
